BOX LINER SPREADING JIG

Joseph Rutkiewicz and Gaspare Grano,
Philadelphia, Pa.

Application October 24, 1945, Serial No. 624,280

1 Claim. (Cl. 93—36.01)

(Granted under the act of March 3, 1883, as
amended April 30, 1928; 370 O. G. 757)

1

The invention described herein may be manufactured and used by or for the Government for governmental purposes, without the payment to us of any royalty thereon.

This invention relates to packaging equipment and more particularly to jigs for placing envelope liners in boxes or containers.

The customary way of lining a box with paper or similar material, or a paper envelope, is to do it by hand. The disadvantage of this method is that it is slow, inexact, causes undesirable wrinkling and soiling of the paper, and results in unevenness in its placement. This frequently defeats its purpose.

It is an object of this invention to provide a new and improved jig for placing linings in containers, that will avoid one or more of the disadvantages and limitations of the prior art.

Another object of the present invention is to provide a new and improved jig for lining purposes that will facilitate the placement of the lining in a container, and then to fit same quasi-automatically in a smooth and expeditious manner.

A further object of the invention is to provide a new and improved lining jig that will be simple but effective in structure and operation, capable of manual application and economical to make.

For a better understanding of this invention, and for further objects thereof, reference is made to the appended drawings and following description, while the scope of the invention is particularly pointed out in the claim.

Referring to the drawings:

Figure 1 is a perspective view showing a lining jig for placement of linings, embodying this invention, in a container.

Figure 2 shows the lining jig folded and placed in a lining envelope.

Figure 3 shows the lining jig opened in the lining envelope, and

Figure 4 indicates the lining jig opened in a lining envelope placed in a crate, the envelope being partly broken away to show the structural relation of the jig in such position.

Similar reference characters refer to similar parts throughout the drawings.

In the construction shown in the drawings, by way of illustration of the invention, an envelope lining jig consists of a structure of a triple-section form, somewhat similar to a book cover with two rigid substantially planiform backs and flexible junction piece. The three sections, 10, 11 and 12, respectively, are arbitrarily termed left, bottom or base, and right of the framework. The left sec-

tion or back 10 is of substantially rectangular shape of open skeleton shape so as to leave an opening 13 in its central area. The right section or back 12 is of similar form and symmetrical therewith, with an opening 14 in its central area. The bottom section or junction base consists of two small frames or base sections 15 and 16 nearly rectangular and of skeleton form with central openings 17 and 18 respectively therein, having 5 hinges 19 joining them together, so they can swing together as in Fig. 2, or outward to lie in a common plane as in Fig. 1, and hinges 20 for swinging the sections 10 and 12 thereto. The outer hinged sides of the frames 15 and 16 are coextensive with the horizontal bottom sides of the backs to which they are hinged. Their right and left horizontal sides have the hinges 20 mounted on their inner surfaces, thus joining the frames 15 and 16 to the backs so they can 10 swing straight out or collapse towards one another. The frames 15 and 16 have their ends 21—22 respectively tapered so that their mutually hinged edges are shortened. The right and left sections have their ends likewise tapered at 15 23 and 24 toward the bottom section 11. The purpose of the taperings is to facilitate insertion of the folded jig into lining envelope 25, which normally is usually folded flat but open at one edge, as indicated in Figure 2. The jig is inserted 20 into the open edge of the envelope after having its two sections 10—12 moved into face-to-face engagement, which also brings the two frames 15—16 together, as shown in Fig. 2. The lining or lining envelope 25, with the folded jig in same 25 is placed in an open box, crate or container 26, by hand. Then the operator pushes the left and right sections 10 and 12 downwardly. The bottom wall of the box obstructs the straightened or apedged toggled frames 15 and 16 of the bottom 30 section, and induces the frames to swing hingedly up flat at right angles to the sections 10 and 11 as they are held by the user in the manipulation of the device. In doing so, the sections 10 and 12, move outwardly in a parallel manner and push 35 the walls of the envelope 25 out, into box form, so that the latter fills up against the inside surfaces of the box 26 and lines it on all sides. The jig may now be removed while the envelope remains open at the top for the material or article to be 40 inserted and covered up by the overlaps of paper. The proportions of the liner envelope and the boxes are partially critical, but the jig itself is not necessarily so, as considerable latitude is permitted, although not necessarily as desirable. 45 This latitude however, permits the jig to be used 55

for several sizes of envelopes, when the operator appreciates the various ways it can be used for the purpose.

The open skeleton nature of the frames facilitates handling as it enables the hands to grasp it firmly in any part. It also allows the user to push his hands through the openings to smooth out any wrinkles that develop, or to remove spots or material that may not be desirable therein.

In practice, it is found that the jig will place linings in containers many times as fast as the old hand method or make-shifts require. It does a better job, prevents soiling and tearing lining. It also facilitates the placing of the article in the box since the lining fits snugly against the walls of the box without crumpling and therefore the full capacity of the box is available for placement of the article. This is especially important where the size of a single article is equal to the full capacity of the box. In such a case, a crumpled envelope would prevent the article from fitting into the box.

While there has been described what is at present considered to be a new and improved embodiment of this invention, it will be noted that various changes and modifications may be made thereon without departing from the principles and spirit of the invention, as sought to be defined in the following claim.

We claim:

A jig for spreading a lining within a container to cause the lining to take substantially the shape of the interior of the container, comprising first and second thin substantially planiform backs, a junction base therebetween, first and second horizontal axis hinges joining the bottoms of said

backs respectively to opposite sides of said junction base, said junction base comprising two substantially identical sections approximately coextensive in width with said backs at said first and second hinges, third horizontal axis hinge means joining said sections mutually, each of said sections having ends that taper inwardly in the direction of said third hinge means, said hinges being all disposed on the inner surfaces of the backs and junction base sections, the bottoms of the backs and the ends of the said backs and base sections having smooth bounding edge surfaces, said jig having a collapsed position with said base sections and said backs face to face in parallel planes and each base section substantially coplanar with its adjoining back, so that while so collapsed said jig may be inserted into a pre-formed collapsed lining envelope and said backs spread laterally apart from each other in said lining, and whereby when said junction base contacts the bottom of said lining envelope and said sections swing into coplanar relation substantially at right angles to said backs said backs are forced apart and said liner envelope is spread substantially smoothly against the bottom and walls of the container.
